UNITED STATES PATENT OFFICE.

THOMAS H. MONAGHAN, OF CHICAGO, ILLINOIS.

AIR HEATER.

1,425,674.

Specification of Letters Patent. Patented Aug. 15, 1922.

Application filed May 12, 1921. Serial No. 468,925.

To all whom it may concern:

Be it known that I, THOMAS H. MONAGHAN, a citizen of the United States and a resident of Chicago, Cook County and State 5 of Illinois, have invented certain new and useful Improvements in Air Heaters, of which the following is declared to be a full, clear and exact description.

This invention relates to air heaters, and 10 its primary object is to increase the efficiency of air heating apparatus; to supply greater volumes of heated air in buildings, with the use of less radiating surface than heretofore; and to circulate the heated air rapidly and to supply a substantially even temperature at all parts of the room heated thereby.

Another object is to provide a unitary structure embodying a large amount of heat 20 radiating surface, arranged to give a maximum of heat efficiency, combined with means for rapidly forcing air past said radiating surface and for deflecting it in any of several directions from the heater. Another 25 object is to provide an air heater of simple, practical and economical construction, having comparatively few parts, easily assembled.

The invention consists in the several novel 30 features hereinafter fully set forth and claimed.

The invention is clearly illustrated in the accompanying drawings, in which:—

Fig. 1 is a front elevation of an air heater 35 embodying a simple form of the present invention; Fig. 2 is a view thereof, partly in side elevation and partly in vertical cross-section, the line of section being indicated at 2—2 in Fig. 1; Fig. 3 is a horizontal section taken on line 3—3 of Fig. 2; and Fig. 40 4 is a vertical cross-section taken on line 4—4 of Fig. 2.

Referring to said drawings, which illustrate one embodiment of the invention, the 45 reference character 5 designates a casing, preferably rectangular in cross-section and formed of four side walls 6 connected together at the corners by suitable reinforcing means. In the lower end of the casing 50 is a fan or blower 7 which is mounted on a shaft 8 journaled in bearing boxes 10 mounted on two opposite side walls 6. The shaft may be driven from any suitable source of power, and I have shown a pulley 11 mounted on it, which pulley may be belted to a 55 drive pulley. Cold air inlet ports 12 in the

opposite sides walls of the casing admit air to the fan or blower and a scroll 9 around the fan, together with the side walls of the casing 5 form the fan casing for the fan or 60 blower. The discharge outlet from said fan casing is directed upward within the casing 5, and above said outlet are a series of steam coils or radiators 13 which leave a tortuous passage for the air. Said steam 65 coils are shown in the form of radiators, and said radiators are supported in said casing in an inclined direction, one overlapping the other, the several radiators inclining in the same direction and being arranged approximately parallel with each other. Conveniently, shelves 14, 15, are secured to the casing and form rests or supports for the radiators. Baffle plates 16 below the lower 70 ends of the radiators and extending parallel therewith, and baffle plates 17 adjacent their upper ends and extending at right angles to the radiators, direct the air currents around the columns of the radiator coils.

Leading to each radiator is a steam supply pipe 18 which has a valve 19 interposed therein and said steam supply pipes 18 run to a header 20 which leads to the source of steam supply. An outlet pipe 21 leads from each radiator and runs to a return pipe 22, 80 which carries the water of condensation back to the steam source. Check valves 23 are placed in the outlet pipes 21 to prevent water from returning to the radiators.

The casing is provided at its upper end 90 with a top member 24 of inverted pyramidal like form, the four sides of which converge downwards from the outer sides of the structure. Frame extensions 24^a support said top member 24. Discharge openings 95 25 for the escape of the heated air, are left between member 24 and top of the casing, and covers 26 are provided for closing any of said discharge openings. Conveniently, said covers may comprise metal sheets or 100 plates 26 arranged parallel with the side walls 6 and held in place on the walls by bolts and nuts 27, the covers having vertical slots to receive the shanks of the bolts for permitting vertical adjustment of the covers. Obviously, the heated air can be directed laterally of the heater, in any of the several directions, or in all directions, by properly adjusting the covers, and in this manner the heated air can be sent in any or 110 every direction laterally, from the heater.

In use, steam is supplied to any or all of

the radiators, depending upon the outside temperature, and the temperature it is desired to maintain in the room where the heater is located, and the fan or blower is set in motion. A large volume of air is thereupon passed through the casing, and because of the abnormally large heat radiating surface in the casing, around which it is forced by the fan, it is quickly heated to the desired temperature and discharged through the discharge openings at the top of the casing in a generally horizontal direction, the field being controlled by the adjustable covers.

15 It has been found in actual practice that, a uniform, comfortable temperature can be maintained in all parts of the room where the heater is installed, and that less radiating surface is required than where individual radiators are used; that a great saving of time and labor results from the installation and use of the heater, and it is economical in use.

More or less variation of the exact details of construction is possible without departing from the spirit of this invention; I desire, therefore, not to limit myself to the exact form of the construction shown and described, but intend, in the following 30 claims, to point out all of the invention disclosed herein.

I claim as new and desire to secure by Letters Patent:

1. An air heater comprising an elongated 35 fan casing, having a cold air inlet opening and a hot air discharge opening, a fan mounted in said casing adjacent said cold air inlet opening, and a series of inclined overlapping steam coils mounted in said 40 casing above said fan, in the path of air currents from the fan to the discharge opening.

2. An air heater comprising a rectangular

elongated fan casing having a cold air inlet opening at its bottom, and discharge openings at its top, disposed around its four sides, a fan mounted in said casing adjacent said cold air inlet opening, and a series of independent radiators mounted in said casing between the inlet and discharge opening, said radiators lying in inclined directions, parallel with and overlapping each other.

3. An air heater comprising a rectangular casing having a cold air inlet opening at its bottom, and discharge openings at its top, disposed around its four sides, a fan mounted in said casing adjacent said cold air inlet opening, a series of independent radiators mounted in said casing between the inlet and discharge openings, said radiators lying in inclined directions, parallel with and overlapping each other, and baffle plates at the tops and bottoms of each radiator.

4. An air heater comprising a rectangular 65 casing having a cold air inlet opening at its bottom, and discharge openings at its top, disposed around its four sides, a fan mounted in said casing adjacent said cold air inlet opening, a series of independent radiators 70 mounted in said casing between the inlet and discharge openings, and an inverted, pyramidal top over said discharge openings.

5. An air heater comprising a rectangular 75 casing having a cold air inlet opening at its bottom, and discharge openings at its top, disposed around its four sides, a fan mounted in said casing adjacent said cold air inlet opening, a series of independent radiators mounted in said casing between the inlet and 80 discharge openings, an inverted, pyramidal top over said discharge openings, and individual covers for said discharge openings adjustably mounted on said casing.

THOMAS H. MONAGHAN.
